UNITED STATES PATENT OFFICE.

JAMES E. CLARK, OF LONG BRANCH, NEW JERSEY, ASSIGNOR TO BARTON A. NICKEN, OF SAME PLACE.

CHURN.

SPECIFICATION forming part of Letters Patent No. 634,847, dated October 10, 1899.

Application filed April 23, 1897. Serial No. 633,453. (No model.)

To all whom it may concern:

Be it known that I, JAMES E. CLARK, a citizen of the United States, residing at Long Branch, in the county of Monmouth and State 5 of New Jersey, have invented certain new and useful Improvements in a Combined Churn and Egg-Beater; and I do hereby declare the following to be a full, clear, and exact description of the invention, such as will enable others skilled in the art to which it 10 pertains to make and use the same.

My invention relates to a combined churn and egg-beater; and the object is to provide a simple, convenient, and effective device of 15 this class for household use; and to this end the novelty consists in the construction, combination, and arrangement of the same, as will be hereinafter more fully described, and particularly pointed out in the claim.

20 In the accompanying drawings the same reference characters indicate the same parts of the invention.

Figure 1 is a perspective view of my combined churn and egg-beater. Fig. 2 is a vertical section of the same. Fig. 3 is a detail view of the dasher. Fig. 4 is a horizontal section.

1 represents the cylindrical churn - body, which may be of any suitable material and 25 size to conform to the quantity of material to be treated, and it is provided with the removable cover 2, which is provided with a central orifice 3 and three equidistant orifices 4 4, arranged concentric with the central 30 orifice 3.

35 5 represents a smaller screen-cylinder open at both ends and formed of closely-interwoven vertical and horizontal strands of resilient wire. This cylinder is provided with stiffening bands or rings 6 7 at its top and bottom 40 edges. On the inner side of said cylinder are three equidistant guard-rods 8, which bear against the stiffening-bands, and the upper ends 9 of said rods project above the upper 45 end of the cylinder and engage the orifices in the cover.

10 represents the cylindrical dasher, and 11 the dasher-rod fixed thereto.

The dasher 10 is guided in its reciprocations and prevented from coming into contact with 50 and injuring the screen-cylinder by the guard-rods 8, and it is formed with two parallel rectangular orifices 12 12.

13 13 represent gravity-valves pivoted to the under side of the dasher and adapted to 55 automatically close the orifices 12 during the downward movement of the dasher and to open during the upward movement of the dasher.

14 14 represent stop-arms on the valves, 60 which abut against the under face of the dasher to limit the open movement of the valves.

Although I have specifically described the construction and relative arrangement of the 65 several parts of my invention, I do not desire to be confined to the same, as such changes or modifications may be made as clearly fall within the scope of my invention.

Having thus fully described my invention, 70 what I claim as new and useful, and desire to secure by Letters Patent of the United States, is—

A churn, comprising a churn body or casing 1 having a cover 2, a screen-cylinder 5 75 inclosed within said casing and formed of closely-interwoven vertical and horizontal strands of resilient wire, stiffening bands or rings 6 7 at the top and bottom edges thereof, guard-rods 9 extending longitudinally on the 80 inner side of the screen-cylinder between the lower stiffening-band thereon and the casing-cover and bearing against said stiffening-bands, and a reciprocating dasher bearing against and guided by said rods, substantially 85 as described.

In testimony whereof I affix my signature in presence of two witnesses.

JAMES E. CLARK.
